BABY BASKET STAND AND ROCKING DEVICE
Jack J. Waldheim, Mequon, and Earl H. Koepke, Milwaukee, Wis., assignors to Martha Friedman, Milwaukee, Wis.

Filed June 26, 1962, Ser. No. 205,358
2 Claims. (Cl. 5—109)

This invention relates to a baby basket stand and rocking device.

The invention consists of a stand having a platform for supporting a baby basket or other unit which is to be oscillated, said stand being provided with legs which will accommodate oscillation in a lateral horizontal plane but not in a longitudinal horizontal plane at right angles thereto, and with a weight which is driven in a horizontal circular path. The legs provide an essentially simple but highly effective means for converting the circular motion of the weight into a lateral oscillation of the stand, which is readily variable as to the rate and extent of oscillation. The chain upon which the weight is supported serves as a speed control, through variation of its length.

In the drawings:

FIG. 1 is a side elevational view of the stand of my invention with a baby basket thereon.

FIG. 2 is an end elevational view.

FIG. 3 is a top plan view of my stand without the baby basket.

FIG. 4 is a cross-sectional view on line 4—4 of FIG. 3.

The drawings disclose a stand for a baby basket having a rigid upper rectangular frame composed of side members 10 and 11, end members 12 and 13, and lateral central brace 14. Legs 15 are secured to each corner of the upper frame, designated generally as 9, and extend outwardly therefrom at a slight angle.

At each end of the device the pair of legs at that end are connected by a lower cross brace 16. The two cross braces 16 are in turn connected by a central horizontal lower brace 17.

Upper lateral cross brace 14 supports a motor 18 which is provided with a cord 19 and a plug 20 to plug into a conventional wall outlet. A switch may be provided if desired.

Motor 18 is secured to the underside of brace 14, as for instance by bolts 22. Motor 18 is of a conventional type which rotates at a speed dependent on the applied load (if the power supply is constant), and preferably is provided with a gear case 23 unitary with the main motor enclosure containing gears which reduce the normal speed of the motor to approximately the desired rate of oscillation of upper framework 9. A motor output shaft 24 extends from gear case 23 and is provided at its lower end with a laterally extending support hook 25 secured to the motor shaft by a screw 26.

A weight 27 hangs from a chain 28 made up of links 29, one of which is engaged with support hook 25 to support the weight on the motor shaft 24.

When switch 21 is turned to a position which supplies current to motor 18 the weight 27 swings in a horizontal circle, the radius, height and circumference of which depends on the speed of motor output shaft 24 and the length of chain 28. The speed is regulated by engaging a different link 29 of chain 28 with hook 25, to change the effective length, height, and radius of the path traveled by weight 27, thus changing the load applied to motor 18

2

through shaft 24 and forcing it to speed up or slow down to a new equilibrium speed. The latter means of adjustment will affect not only the speed of rotation but also the magnitude of the oscillation imparted to stand 9 by rotation of the weight. When the chain is shortened the oscillations become more frequent, but decrease in magnitude.

The legs are made of relatively thin sheets of resilient material such as $\frac{3}{16}$ " hardboard, having only moderate resistance to flexing in a plane at right angles to their surfaces. They are attached to the sides of top frame 9 by wood screws 30, or other conventional fastening devices, so that the plane of the surface of leg 15 extends longitudinally of the upper frame 9, and are so shaped that they incline longitudinally downwardly and outwardly, to give further longitudinal stability. As best shown in FIGS. 2 and 3, the outside edges of side members 10 of top frame 9 are inclined laterally downwardly and outwardly so that attached legs 15 also incline slightly laterally downwardly and outwardly to give the upper support frame 9 lateral stability when motor 18 is not in operation, despite the lateral resilience of legs 15. This lateral support must not be so great that it prevents lateral oscillation of the frame on the legs under the influence of weight 27 revolving about shaft 24.

The angles at which legs 15 are placed, their resilience, the speed of motor 18, and the mass of weight 27, are chosen to overcome the stabilizing forces due to the lateral inclination of legs 15 only when motor 18 is in operation, and to impart a lateral oscillation of the desired period and magnitude to stand 9, in view of the mass to be placed on stand 9, such as baby basket 31. Rotation of weight 27 is not able to impart a longitudinal oscillation to stand 9 because of the width of legs 15 and their greater inclination in the longitudinal plane than in the lateral plane. Accordingly, baby basket 31 will oscillate laterally at a controllable speed in a simple but effective manner.

It will, of course, be appreciated that other rotating devices could be used to supply power to rotate the weight and to regulate the speed of the oscillation produced thereby, for instance a spring motor equipped with a speed regulating escapement or with a flyball governor could be substituted for motor 18. A rheostat could also be incorporated in switch 21 for motor 18, but chain 28 is the preferred speed control.

It will be seen that applicant has provided an extremely simple but effective device for rocking a baby which converts the revolution of a weight to a lateral rocking motion of the upper platform portion of a stand for a baby basket 50 by means of the construction and inclination of the flexible legs of the stand, and regulates the speed thereof by varying the length of the support for the weight and the mass of the weight.

The working parts of my device may be covered, if desired, but this is not essential. It may also prove desirable to cover the weight with a soft cover to prevent accidents to children.

The word "platform" as used herein refers to a structure extending in a generally horizontal plane which is capable of supporting a baby basket or the like, regardless of whether the platform is closed or open in construction.

We claim:

1. A stand for a baby basket comprising a rigid upper horizontal platform, a plurality of laterally resilient longitudinally rigid supports for said platform, a weight, and

means attached to said platform for revolving said weight in a horizontal plane, flexible weight-supporting means between said weight and said means for revolving said weight, said weight-supporting means being adjustable in length, each of said plurality of supports comprising a sheet of material which is laterally thin and resilient and is longitudinally wide and nonflexible.

2. The device of claim 1 in which each said sheet of material is inclined downwardly and outwardly from said platform in both the lateral and the longitudinal planes, 10 said inclination being greater in the longitudinal plane.
